CLAIM

The ornamental design for a mandible shield, as shown and described.

DESCRIPTION

FIG. 1 is a front perspective view of a mandible shield showing my new design coupled to an optional helmet; FIG. 2 is a front perspective view of the mandible shield shown in FIG. 1;

FIG. 3 is a rear perspective view of the mandible shield shown in FIG. 1;

FIG. 4 is a front elevational view of the mandible shield shown in FIG. 1;

FIG. 5 is a rear elevational view of the mandible shield shown in FIG. 1;

FIG. 6 is a left-side elevational view of the mandible shield shown in FIG. 1;

FIG. 7 is a right-side elevational view of the mandible shield shown in FIG. 1;

FIG. 8 is a top plan view of the mandible shield shown in FIG. 1; and,

FIG. 9 is a bottom plan view of the mandible shield shown in FIG. 1.

The broken lines shown in the drawings represent portions of the mandible shield that form no part of the claimed design.

1 Claim, 9 Drawing Sheets
